UNITED STATES PATENT OFFICE.

JOSHUA VALENTINE EVES, OF BELFAST, IRELAND.

MACHINE FOR DRAWING FLAX AND OTHER LONG-STAPLE FIBERS TO FORM SLIVERS OR YARN.

1,132,316.

Specification of Letters Patent. **Patented Mar. 16, 1915.**

Application filed November 23, 1912. Serial No. 733,146.

To all whom it may concern:

Be it known that I, JOSHUA VALENTINE EVES, a British subject, residing at Belfast, county Antrim, Ireland, have invented certain new and useful Improvements in Machines for Drawing Flax and other Long-Staple Fibers to Form Slivers or Yarn, of which the following is a specification.

This invention relates to machines for drawing flax, wool and other long staple fibers for forming slivers or yarn, and is designed to produce a sliver of greater uniformity.

In such machines commonly known as gill frames, the fibers are fed into retaining rollers and carried by a series of moving fallers to the drawing rollers, the drawing rollers rotating at a constant speed irrespective of any variation in the weight or thickness of the material fed thereto.

The invention consists essentially in automatically changing the speed of the drawing rollers relatively to that of the retaining rollers consequent to a variation in the separation or displacement of the latter by a change of thickness of material passing between them and in delaying such change until the material which caused the displacement has been passed forward by the gills and fallers to or nearly to the nip of drawing rollers irrespective of the distance such rollers are from the retaining rollers, which in machinery for dealing with long fibers like flax or wool is a considerable distance. Also in connecting an indicator or indicators therewith for the purpose of showing the regularity with which the material is being fed to the machine, and in an arrangement of the levers operated by the movement of the retaining rollers to connect a multiple set of rollers with the main operating lever. Mechanism which accomplishes this change of draft at the right time may be called "a delaying motion" because though actuated by the retaining rollers it delays effecting any change of speed or draft of the drawing rollers till the portion of the material necessitating the change has traveled over the intervening distance.

The invention will be fully described with reference to the accompanying drawings.

Figure 1, side elevation of spread board partly in section showing the invention applied thereto. Fig. 2, front elevation of same with the drawing rollers and fallers removed. Fig. 3, front elevation of parts of same showing a relay motion to actuate the belt shifter of the cone drums and relieve the pressure on the pins and levers of the motion. Fig. 4, sectional detail of peg *n* and wheels *M²* *M³*. Fig. 5, front elevation similar to Fig. 1, showing the indicating finger. Fig. 6, front elevation showing the arrangement of levers to a double sliver spread board. Fig. 7, side elevation of same. Fig. 65 8, front elevation showing the arrangement of levers for a four sliver spread board. Fig. 9, side elevation of same.

The machine is constructed in the ordinary way with retaining rollers *A* and *B*, drawing rollers *A'* and *B'* and fallers or gill bars *B²* between the two sets of rollers. Upon the journals of the top retaining or pressing roller *B* two balance levers *C* and *C'* are mounted with a fulcrum at *b* against the knife edge on a transverse bar *c*. The balance levers *C* *C'* are at their other ends connected or linked by weight wires or rods *D* *D'* to a transverse lever *E* pivoted at or near its center by a link *F* to a weight lever *G* pivoted on a fulcrum pin *H* on a bracket *h*. The weight lever *G* extends forward to the front of the machine and upon it is placed an adjustable weight *W* to give the desired amount of pressure to the top retaining roller *B*, and at its end it engages or is connected to a bell crank lever *J* pivoted on a stud *k* projecting from a bracket *K*. The upright member of the lever *J* oscillates to one side or the other as the thickness of material passing between the retaining rollers varies. To the end of the lever *J* a link *M* is pivoted to connect with the "delaying motion" wheel *N*. To the link *M* is connected an index finger *L* with an indicator plate *L'* so that the rising and falling movement of the retaining roller *B* and consequently any variation in the feeding of the material can be readily observed.

At one side of the machine a large wheel *N* is mounted fitted around its rim with a series of loose pieces or pegs *n* free to slide

to and fro endwise across the wheel and above the wheel is mounted a shoe or oscillating device M' with two contact pads $m\ m'$ which as the delaying wheel N rotates 5 engages the pegs n and moves them backward and forward according to the position of the contact pads $m\ m'$. The oscillating shoe M' is connected by the link M with the bell crank lever J and through it is rocked at each rise and fall of the 10 top retaining roller B thereby moving the pegs n to one side or other of the delaying wheel N . Below the delaying wheel N a somewhat similar rocking shoe O is mounted 15 with which the pegs n in succession engage as the wheel rotates giving a corresponding rocking motion thereto at a predetermined period of time after the pegs n have been set by the shoe M' . The motion 20 of the lower rocking shoe O is transmitted through the arm O' , link or rod O^2 , lever O^3 , link O^4 and levers O^5 and O^6 to the belt fork or belt shifter O^7 and thereby alters or adjusts the position of the driving 25 belt on the cone pulleys P and P' . The pegs n may be retained in position in the wheel N by any suitable means; at present it is preferred to make the pegs with annular V-shaped collars or grooves at one 30 end and as the wheel N rotates these engage two locking wheels M^2 M^3 before they encounter the shoe O to prevent any side movement or slipping of the pegs n . The wheels M^2 and M^3 are carried on studs on the 35 ends of weight levers m^2 m^3 and on their periphery are formed with annular grooves to engage the collars on the pegs n and hold or lock them in position and the pegs after being thus locked impart a side motion to 40 the bottom rocking shoe O .

The drawing roller A' is driven through a differential gear box P^4 of any suitable form and on the shaft of the driven cone pulley P' is a pinion P^2 gearing into the 45 wheel P^3 of the differential gear P^4 and accordingly the speed of the drawing roller A' is accelerated or retarded according to the speed at which the cone P' is driven. And as the rise and fall of the top retaining 50 roller B adjusts and governs the position of the belt on the cone pulleys and the speed of the driven pulley P' it also alters the speed of the drawing roller A' at such a period of time after such rise or fall takes 55 place as may be determined by the speed or adjustment of the delaying wheel N . To enable the pegs n of the wheel N to more easily move the belt on the cone pulleys $P\ P'$ a relay motion shown in Fig. 3, 60 may be inserted between the lever O^3 and the strap fork O^7 which is put in motion from the shoe O through arm O' link O^2 and lever O^3 .

Connected to the lever O^3 is a reciprocating

lever R which oscillates a lever T when 65 the shoe O is operated. The lever T is formed with projections t and t' which normally hold two pivoted pawls $u\ u'$ out of engagement with the two racks $V\ V'$ the racks V and V' being cut with ratchet 70 teeth in opposite directions. The pawls u and u' are kept constantly oscillating at a high speed by the eccentric U and levers u^2 and u^3 . Should the lever T be oscillated in either direction by the shoe 75 O it allows one of the pawls u or u' to engage one of the racks V or V' and to continue pushing one tooth at a time until the shoe O gets back to normal position. The racks V and V' are connected to the belt shifter O^7 by the link v 80 and lever O^6 . To make the delaying motion self-contained so as to be easily put on existing machines the top and bottom shoes M' and O , delaying wheel N , weight levers m^2 and m^3 and wheels M^2 and M^3 are all carried on one bracket S and can be readily bolted to any existing machines.

In a double sliver machine as in Figs. 6 and 7 the levers C are preferably carried 90 out to the back of the machine and the links $D\ D'$ placed in front of the rollers. The links $D\ D'$ of each retaining roller B are connected to a transverse lever E and the two levers E are similarly connected by 95 links to a lever E' which in turn is connected by a link F to a main operating lever G which operates the bell crank lever J as before described. To the link M which connects the lever J with the delaying motion I connect an index finger L provided with an index plate L' . To each pair of balance levers C I may also connect a transverse lever e by links f and to the lever e connect index fingers L^2 with index plate 10 L^3 by links e' to show separately the movement of the retaining rollers B . The index fingers L^2 will serve as a guide in the spreading of the fibers on the spread boards and the main index finger L will show the 11 average of the doublings. Thus if one roller is feeding light and the other roller is feeding heavy the main index finger L will stand at normal or zero while one finger L^2 will stand at light and the other 11 finger L^2 will stand at heavy.

In a four sliver machine as in Figs. 8 and 9 the levers C are preferably carried out to the back of the machine and the links D and D' suspended therefrom. The links 12 $D\ D'$ of each retaining roller B are connected to a transverse lever E and each pair of levers E are similarly connected by links to a transverse lever E' and the two levers E' similarly connected by links to a lever 12 E^2 which in turn is connected by a link F to the main operating lever G , which operates the bell crank lever J as before de-

scribed. To the link M which connects the lever J with the delaying motion I connect an index finger L provided with an index plate L'. To each pair of balance levers C 5 I may also connect a transverse lever e by links f and to the lever e connect index fingers L², with index plates L³ by links e' to show separately the movement of each pair of retaining rollers B. The index fingers 10 L² will serve as a guide in the spreading of the fibers on the spread board and the main index finger L will show the average of the doublings. Thus if one roller is feeding light and the other roller is feeding heavy 15 the main index finger L will stand at normal or zero, while one finger L² will stand at light and another finger L² will stand at heavy.

In the arrangements shown in Figs. 6 20 and 8 it may be found necessary to positively drive the top retaining roller B. In the case shown in Fig. 6 the roller B is driven by a wheel b at the end of each roller driven from the ordinary gearing on the machine. 25 In the case shown in Figs. 8 and 9 a wheel b is placed on the end of each roller B and a top shaft b² is placed above the rollers with wheels b' thereon to gear with the wheel b and drive each roller B.

30 What I claim as my invention and desire to protect by Letters Patent is:—

1. In an apparatus for drawing long staple fibers, the combination with relatively displaceable retaining rollers and with 35 drawing rollers to which the material is passed from the retaining rollers, of means for varying the speed of the drawing rollers in accordance with variations in the thickness of the material passing through the retaining rollers, and means for delaying the 40 speed variation of the drawing rollers until the particular thickness of material which has initiated such variation has moved forward to, or nearly to, the nip of the drawing rollers.

45 2. In an apparatus for drawing long staple fibers, the combination with retaining rollers and drawing rollers to which the material is passed from the retaining rollers, of means for varying the speed of the drawing rollers in accordance with variations in the thickness of the material passed by the retaining rollers, and means whereby the speed variations of the drawing rollers are 50 synchronized with the passage thereto of the lengths of the material which have initiated such variations.

60 3. In an apparatus for drawing long staple fibers, the combination with a top retaining roller which is raised and lowered in accordance with variations in the thickness of the material passed thereby, drawing rollers, gearing for operating the drawing rollers, levers which are raised and lowered

65 by the rise and fall of the retaining roller, and a delay motion interposed between said levers and said gearing and operable through said gearing to vary the speed of rotation of the drawing rollers in accordance with variations in the thickness of the material 70 passed by the retaining roller.

4. In apparatus for drawing flax, wool and other long staple fibers the combination with the top retaining roller of levers which are raised and lowered by the rise and fall 75 of the roller, drawing rollers, driving mechanism for said drawing rollers and including a speed change device, a delaying motion operatively connected to said levers and by which the movement of the roller is 80 transmitted after a lapse of time and operative connections between said delaying motion and said change speed device.

5. In an apparatus for drawing flax, wool and other long staple fibers including a top 85 retaining roller and drawing rollers to which material is passed from the top retaining roller, the combination of levers which are raised and lowered by the rise and fall of the top retaining roller, a link and lever system connected thereto for transmitting such movement, a rocking shoe to which the movement is transmitted by said system, a wheel rotating within the shoe and provided adjacent its rim with loose transversely 90 movable pegs operable by the rocking of the shoe, a second rocking shoe operable by said pegs, gearing for operating said drawing rollers, a change speed device for said gearing, and a second system of levers and links 95 connecting the second shoe with said change speed device.

6. In an apparatus for drawing long staple fibers, the combination with relatively displaceable retaining rollers, drawing rollers, driving mechanism for the drawing rollers, and a change speed device for said driving mechanism, of means whereby the rise and fall of the upper retaining roller is 100 effective to operate said change speed device and including a delaying motion for causing the operation of said change speed device a predetermined length of time after the rise or fall of said retaining roller, and a relaying motion interposed between said 105 delaying motion and said change speed device.

7. In apparatus for drawing flax, wool and other long staple fibers the combination with the retaining rollers, of levers which are raised and lowered by the rise and fall 120 of the top retaining roller, links and levers connected thereto for transmitting such movement, a rocking or oscillating shoe to which the movement is transmitted, a wheel rotating within the shoe and provided adjacent its rim with loose transversely movable pegs operable by the rocking of the shoe,

- a second shoe rocked by the said pegs, a strap shifter, a system of levers and links connecting the second shoe with said strap shifter, a pair of cone pulleys and a differential driving mechanism to drive the drawing rollers and a relay motion interposed in said system of levers and links.

Copies of this patent may be obtained for five cents each, by addressing the "Commissioner of Patents, Washington, D. C."

In testimony whereof I have hereunto set my hand in presence of two subscribing witnesses.

JOSHUA VALENTINE EVES.
